9 Claims. (Cl. 24—20)

This invention relates to a hoop iron for wrapping round bales, which has at its ends couplings formed by incisions and curved webs and adapted to be manually hooked together.

Hitherto, in these couplings the halves to be hooked together have been designed of different shape in that at one end of the hoop iron the central web formed by the symmetrical arrangement of a pair of incisions is narrower than that formed at the other end of the hoop iron, so that narrower central web can be inserted into the space between the two outer webs of the other coupling half. The manufacture of such different coupling halves requires the use of different tools.

It is the object of the present invention to provide a hoop iron of the kind specified above, which has coupling halves that can be manufactured with the aid of one and the same tool.

This object is achieved in that the incisions are increased in width such that the coupling halves can be unimpededly selectively hooked together despite their similar shape. This substantially simplifies the manufacture of hoop irons especially for wrapping round bales of different sizes and enables the hoop iron to be made of a great length wherein the hoop iron is provided with a continuous series of couplings which can be selectively hooked together. For wrapping the hoop iron around a bale, it is only necessary to separate the length required and the ends of the hoop iron are then hooked together. Furthermore, the hoop iron may be re-used for wrapping round larger or smaller bales. For wrapping round larger bales, several hoop irons can be hooked together at their ends whereas if smaller bales are intended to be wrapped round, the hoop iron only needs to be shortened to the length required. In couplings in which the central web formed by the incisions increased in width is twice reduced in width so that it has a broader middle portion and two smaller end portions, the ends of the hoop iron can be exchanged when they are to be hooked together, i.e. each end of the hoop iron can be selectively disposed above or below the other end of the hoop iron and hooked therein.

Expediently, the incisions may be increased in width by narrowing and thickening in cross-section the central webs and/or the outer webs formed by the incisions. The cross-sectional area of the hoop iron is not reduced by increasing the width of the incisions, so that the strength of the hoop iron is retained. This advantage is also utilized in the case of increasing the incisions in width by deforming the central webs and/or the outer webs so that they are given a cross-section of arcuate shape or forcing apart the outer webs or turning them into inclined positions with respect to the plane of the hoop iron.

Advantageously, the incisions increased in width may also be formed by narrow gaps cut out of the hoop iron. Thereby the manufacture of the couplings is substantially simplified as the tools for cutting the gaps out of the hoop iron and those for producing the curved webs act in the same direction and, therefore, can be combined into one tool.

It may be expedient to increase in width only the parts of the incisions extending substantially in the longitudinal

2

direction of the hoop iron. Thereby couplings having a central web which is only once reduced in width at each side, can be readily hooked together, the parts of the hoop iron engaging behind one another and forming the connection being not reduced. To enable couplings having a central web which is twice reduced in width at each side to be readily hooked together, expediently at least one of those parts of the incisions forming the reductions in width of the central web is increased in width.

Advantageously, the increased incisions taper toward their ends. This has a favourable influence on the flux of the lines of force in the hoop iron in the region of the couplings, preventing the hoop iron from breaking particularly at the ends of the incisions.

Several preferred embodiments of the invention will now be described by way of example and with reference to the accompanying drawings, in which:

FIG. 1 is a perspective view of a bale provided with a plurality of hoop irons according to the invention;

FIG. 2 is a top plan view, on a larger scale, of a first embodiment of the connection of the hoop irons;

FIG. 3 is a side elevational view of the connection shown in FIG. 2;

FIG. 4 is a top plan view, on a larger scale, of a second embodiment of the connection of the hoop irons;

FIG. 5 is a similar view of a third embodiment of the connection of the hoop irons;

FIG. 6 is a perspective view of an eccentric press for the manufacture of the hoop iron according to the invention;

FIGS. 7 to 9 are schematic cross-sectional views of the tools for producing the incisions in the hoop iron and for narrowing and thickening in cross-section the central webs and/or the outer webs formed by the incisions;

FIGS. 10 to 12 are similar views of the tools for producing the incisions in the hoop iron and for deforming the central webs and/or the outer webs so they are given a cross-section of arcuate shape;

FIGS. 13 to 15 are similar views of the tools for producing the incisions in the hoop iron and for forcing apart the outer webs;

FIG. 16 is a fragmentary top plan view of the hoop iron produced by the tools shown in FIGS. 13 to 15;

FIGS. 17 and 18 are schematic cross-sectional views of the tools for producing the incisions in the hoop iron and for turning the outer webs into inclined positions with respect to the plane of the hoop iron;

FIGS. 19 and 20 are similar views of the tools for producing the incisions formed by narrow gaps, and

FIG. 21 is a top plan view, on a larger scale, of a fourth embodiment of the connection.

Referring now to the drawings, FIG. 1 shows a bale 22 which is provided with hoop irons 23, one hoop iron being arranged in the longitudinal direction of the bale and three other hoop irons being arranged in the transverse direction thereof and at a distance from each other. For producing the bale 22 provided with the hoop irons 23, the material for the bale is compressed. Then the hoop irons 23 are wrapped around the compressed material, which hoop irons are adapted to be hooked together at their ends. To this end the hoop irons 23 are provided particularly at their ends with one or more couplings which are formed by angular incisions 24 extending substantially in the longitudinal direction of the hoop iron.

As shown in FIG. 2, the angular incisions 24 are symmetrically arranged in pairs and are substantially Z-shaped. A central web 25 and two outer webs 26 are formed by the incisions 24, which webs are alternately curved in opposite directions longitudinally of the hoop iron 23, as can be seen from FIG. 3.

FIG. 6 shows an eccentric press 27 which serves for

the production of the incisions 24 in the hoop irons 23 and is provided in a known manner with a table 28 and a die 29 arranged thereabove. The die 29 is movable up and down via an eccentric which can be connected through a fluid coupling to a flywheel driven by an electric motor. For operating the eccentric press 27 it is therefore necessary first to start the electric motor driving the flywheel. For this purpose an off-on switch 30 is provided on the table 28. The table 28 is further provided with a second off-on switch 31 for operating the fluid coupling. Upon actuation of the off-on switch 31 the fluid is compressed. The eccentric press is now ready for operation and the die 29 can be moved up and down, according to choice, by operating hand levers 32 and 33 or a foot switch 34 hydraulically coupling the eccentric of the die 29 with the flywheel.

On the table 28 of the eccentric press 27 a punching tool 35 is arranged which, in the illustrated embodiment, is constructed as a tool guided by columns. The punching tool 35 has a base plate 36 with a lower cutting plate 37 arranged thereon. The base plate 36 is provided with columns 38 on which a guide plate 38 is movable up and down. Secured to the die 29 is a tenon plate 40 of the punching tool 35 on which an upper cutting plate 41 is provided. The upper cutting plate 41 projects into a recess in the guide plate 39. The hoop iron to be worked is guided between the lower cutting plate 37 and the guide plate 39. Upon downward movement of the die 29 the tenon plate 40 together with the upper cutting plate 41 secured thereto is moved toward the lower cutting plate 37 and during this movement first the guide plate 39 which is connected with the tenon plate 40 is pressed by means of springs 42 against the lower cutting plate 37 so that the hoop iron is fixedly held in place. Upon further downward movement of the die 29 the upper cutting plate 41 and the lower cutting plate 37 engage into each other thereby to produce the incisions 24 in the hoop iron lying between them. At the same time the webs 25 and 26 formed by the incisions 24 are alternately curved in opposite directions longitudinally of the hoop iron. As can be seen particularly from FIGS. 2, 4, 5, 16 and 21, the angular incisions 24 are increased in width so that the central web 25, in spite of its oblique edges which result from the punching process (see FIGS. 7, 10, 13 and 17), can be inserted between the two outer webs 26 of another pair of incisions 24 produced with the aid of the same punching tool 35 in order to hook the ends of the hoop iron 23 together. To be able to increase the width of the incisions 24, the punching tool 35 comprises follow-on tools. In the embodiments illustrated in FIGS. 7, 8, 9, 10, 11, 12, 13, 14, 15, 17 and 18, at a first working place one or more pairs of incisions 24 are produced while the so formed webs 25 and 26 are alternately curved in opposite directions longitudinally of the hoop iron and at a second working place the incisions 24 are increased in width. After each working stroke of the eccentric press the hoop iron is moved forwardly by a known gripper feed mechanism 43 by the width of one working place.

FIG. 7 shows the upper cutting plate 41 and the lower cutting plate 37 at the first working place where the incisions 24 are produced and the so formed webs 25 and 26 are alternately curved in opposite directions longitudinally of the hoop iron. At the second working place shown in FIG. 8, the central webs 25 bent out of the plane of the hoop iron are narrowed and thickened in cross-section. To this end horizontally movable dies 44 are provided which can be moved toward each other by means of wedges provided on the tenon plate 40 of the punching tool 35, and which can be returned into their initial positions by springs. However, as shown in FIG. 9, it is also possible for the outer webs 26 to be narrowed and thickened in cross-section of the second working place by a downwardly tapering die 45 provided on the tenon plate 40. It is understood that also both

the central webs 25 and the outer webs 26 may be narrowed and thickened in cross-section.

FIGS. 10 to 12 illustrate an embodiment wherein the incisions 24 are increased in width by deforming the webs 25 and 26 formed by the incisions 24, in such a manner that the webs are given a cross-section of arcuate shape. FIG. 10 shows the first working place where the incisions 24 are produced and the so formed webs 25 and 26 are alternately curved in opposite directions longitudinally of the hoop iron. At the second working place shown in FIG. 11, the central webs 25 are so deformed that they are given a cross-section of arcuate shape. To achieve this, the tenon plate 40 is provided at the second working place with forming dies 46 which are arranged to cooperate with correspondingly shaped molds 47 provided on the base plate 36. Alternatively, as can be seen from FIG. 12, also both the central webs 25 and the outer webs 26 can be given a cross-section of arcuate shape at the second working place. It is, however, also possible to deform only the outer webs 26 in the manner indicated.

In the embodiment illustrated in FIGS. 13 to 15 the incisions 24 are increased in width by forcing the outer webs 26 apart. FIG. 12 again shows the first working place where the incisions 24 are produced and the so formed webs 25 and 26 are alternately curved in opposite directions longitudinally of the hoop iron. At the second working place (FIG. 14) the outer webs 26 are forced apart by horizontally movable hooks 48 which can be moved in opposite directions by a wedge provided on the tenon plate 40. Alternatively, as shown in FIG. 15, the outer webs 26 can be forced apart by downwardly tapering dies 49 provided on the tenon plate 40. By thus forcing apart the outer webs 26 the hoop iron 23 is given a bellied shape in the region of the incisions 24, as can be seen from FIG. 16.

FIGS. 17 and 18 illustrate an embodiment wherein the incisions 14 are increased in width by turning the outer webs 26 into inclined positions with respect to the plane of the hoop iron. FIG. 17 again shows the first working place where the incisions 24 are produced and the so formed webs 25 and 26 are alternately curved in opposite directions longitudinally of the hoop iron. At the second working place shown in FIG. 18, the outer webs 26 are turned into inclined positions with respect to the plane of the hoop iron. To this end, forming dies 50 are provided on the tenon plate 40 in the region of the second working place, which forming dies are arranged to cooperate with correspondingly shaped molds 51. It is understood that the turning of the outer webs may be effected contemporaneously with the making of the incisions by so constructing the parts of the surface of the lower cutting plate 37 supporting the outer webs that they extend at an incline with respect to the plane of the hoop iron.

In the embodiment illustrated in FIGS. 2, 5, 19, 20 and 21 the incisions 24 are increased in width by cutting narrow gaps 52 out of the hoop iron. As can be seen from FIG. 19, at the first working place the gaps are cut out by narrow cutting die 53. At the second working place shown in FIG. 20, the webs 25 and 26 formed by the gaps are alternately curved in opposite directions longitudinally of the hoop iron by forming dies 54 and molds 55.

The incisions 24 formed in accordance with the invention enable the hoop iron to be made of a great length, the hoop iron being provided with a continuous series of similar incisions 24 increased in width which can be selectively hooked together. For wrapping the hoop iron around a bale, it is only necessary to separate the length required and the ends of the hoop iron are then hooked together. Furthermore, the hoop iron may be repeatedly used. If the hoop iron is intended to be subsequently wrapped around a bale of smaller size, the hoop iron only needs to be shortened to the length required. The ends of the hoop iron can then be hooked together again

owing to the continuous arrangement of the incisions 24. For wrapping around larger bales, several hoop irons 23 can be hooked together at their ends.

In FIG. 5 the central web 25' formed by the incisions 24' is twice reduced in width so that it has a broader middle portion and two smaller end portions. This enables the ends of the hoop iron to be exchanged when they are to be hooked together, i.e. each end of the hook iron can be selectively disposed above or below the other end of the hook iron and hooked therein. To ensure that the ends of the hook iron can be readily hooked together, either the whole incisions are increased in width or in addition to the parts of the incisions extending substantially longitudinally of the hoop iron, also one of those parts of the incisions forming the reductions in width of the central web is increased in width.

This invention may be embodied in other specific forms without departing from the spirit or essential characteristics thereof. The present embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein. For example, as shown in FIG. 21, only one incision 24" of each pair of incisions 24 may be increased in width so that the central web 25" can be manually inserted between the outer webs of another pair of corresponding incisions.

I claim:

1. A strapping device including an elongated flexible band being at least at each end portion thereof formed with a pair of zig-zag shaped substantially longitudinally extending slits which are of identical configuration and spacing from each other in all pairs and in which the slits in each pair are symmetrically arranged with respect to an axis extending in longitudinal direction of said band and define between themselves a central web and between said slits and the longitudinal edges of said band a pair of outer webs, at least said central web between each pair of slits being raised out of the plane of the band so that when said end portions are overlapped during strapping of a package with one central web at one end portion overlapping the central web of the other end portion and nested in part between the pair of outer webs of said other end portion, the side edges of said one central web will interlock with the facing side edges of said outer webs of said other end portion, the width of said slits being widened in transverse direction so that, though all of said central webs have identical widths and configurations, said end portions may be manually interlocked in any overlapping relationship with each other.

2. A strapping device as set forth in claim 1 in which said slits are widened so that the widths thereof taper toward the ends thereof.

3. A strapping device as set forth in claim 1 in which each of said slits has a pair of spaced longitudinally extending end portions substantially parallel to the longitudinal axis of the band, a central portion substantially parallel to said axis and spaced further therefrom than said pair of end portions, and a pair of connecting por-

tions inclined to said axis and connecting said central portion with said end portions, respectively.

4. A strapping device as set forth in claim 1 in which only one slit in each pair of slits is widened.

5. A strapping device as set forth in claim 1 in which said outer webs are bent out of the plane of the band in a direction opposite to the bend of the central web.

6. A strapping device as set forth in claim 1 in which said elongated flexible band is formed along the whole length thereof with said pairs of zig-zag shaped identical slits spaced in longitudinal direction from each other and in which at least said central web between each pair of slits is bent out of the plane of the band and in which at least one of the slits in each pair of slits is widened.

15 7. A strapping device as set forth in claim 1 in which each of said slits has a pair of spaced longitudinally extending slit portions substantially parallel to the longitudinal axis of said band and a connecting portion inclined to said axis.

20 8. A strapping device as set forth in claim 7 in which only the longitudinally extending slit portions are widened.

9. A strapping device including an elongated flexible band being at least at each end portion thereof formed with a pair of zig-zag shaped substantially longitudinally extending slits which are of identical configuration and spacing from each other in all pairs and in which the slits in each pair are symmetrically arranged with respect to an axis extending in longitudinal direction of said band and define between themselves a central web and be-

30 tween said slits and the longitudinal edges of said band a pair of outer webs, at least said central web between each pair of slits being raised out of the plane of the band so that when said end portions are overlapped during strapping of a package with one central web at one end

35 portion overlapping the central web of the other end portion and nested in part between the pair of outer webs of said other end portion, the side edges of said one central web will interlock with the facing side edges of said outer webs of said other end portion, the width of

40 said slits being widened in transverse direction so that the transverse width of each central web at any point spaced in longitudinal direction from the ends of said slits defining said central web is slightly smaller than the transverse width between the facing side edges of the outer

45 webs at any points equally spaced from the ends of said slits, whereby, though all of said central webs have identical widths and configurations, said end portions may be manually interlocked in any overlapping relationship with each other.
